KINGSLEY L. MARTIN, OF MONTCLAIR, NEW JERSEY

WATER TUBE BOILER CONSTRUCTION

Application filed November 29, 1929. Serial No. 410,428.

The invention relates to steam boilers of the water tube type and more particularly to those having straight tubes inclined somewhat from the horizontal with water compartments at their ends and a steam and water drum above the tubes. Difficulty has been experienced in baffling boilers of this type in such a manner as to secure complete combustion and avoid the production of heavy smoke with certain grades of coal. One method of baffling employed involves the use of a plurality of horizontal baffles. This system is open to the objection that dead spaces are formed where little or no gas passes over the heating surface of the tubes. The movement of the gases longitudinally of tubes has also been found to involve a relatively lower degree of heat transfer than that present when the gases flow transversely of the tubes. Another method of baffling permits the gases from the furnace to pass up directly completely through the bank of tubes where they are reversed and made to flow down through the tubes followed by a second reversal and a flow upward again through the tubes. This method, while efficient, produces heavy smoke, particularly with fuels of high volatile content, as the gas enter the cool spaces between the tubes before combustion is completed. My invention is designed to combine the best features of the methods heretofore used and to overcome the objections to such methods as above pointed out. One form of the invention is illustrated in the accompanying drawing, wherein:

The figure is a longitudinal section partly in side elevation of a steam boiler embodying the invention.

Referring now to the drawing, 1 is the front wall and 2 is the bridge wall of a furnace, the upper portion of the combustion chamber of which is indicated at 3. The water tubes of a horizontal water tube boiler are located above the furnace and may be in one group as shown at 4, or may be subdivided into upper and lower groups; but the grouping of the tubes is not material to my invention. The tubes are connected at one end to downtake headers 5, and at the other end to uptake headers 6. The uptake headers are con-

nected to the longitudinal drum 7 by short nipples 8, and the downtake headers by long nipples 9. In certain forms of boilers, a cross drum is used and a different method of connecting the headers is used, but this is not material to my invention.

The baffle construction comprises four parts; first, a lower horizontal baffle 10, which may be laid on one of the two lower rows of tubes, but preferably surrounds the lower row of tubes, so as to form a continuous refractory roof for the furnace. Second, a lower cross baffle 11 preferably inclined toward the nearest header 5. This inclination tends to prevent the accumulation of soot and slag; decreases the entering velocity of the gases, maintains substantially uniform velocity of flow, and forces the gases across the tube so that the scrubbing action of the gases and the heat transfer are at the maximum.

Third, an upper cross baffle 12 also preferably inclined and nearly parallel to the lower cross baffle is used to direct the gases downward across the tubes forming a second pass and, after reversal in the lower part of the tube space below the baffle 12, the gases again cross the tubes in the third pass and flow to the outlet of the boiler 14.

Fourth, an upper horizontal baffle 13 is laid preferably on the top row of tubes to prevent the gases which are ascending the first pass from going directly to the boiler outlet 14, directing them instead downwardly into the second pass.

If a restricted space between the steam drum or drums make it advisable to lay the upper horizontal baffle 13 on other than the top row, this can be readily done without affecting the arrangement shown otherwise than to shorten by a corresponding amount the lower cross baffle 11, if necessary, to provide adequate area between the first and second passes.

A superheater, not shown, of any of the usual types may be located in the space between the upper baffle 13 and the steam drum 7, or it may be located in the bank of tubes by omitting any desired number of tubes to make room for it.

It will be seen that by placing the lower

- 5 baffle 10 on the lower row of tubes, a refractory roof is formed which is highly heated by the radiant heat from the fuel and by contact with the hot gases of combustion, and this heat is partly transmitted to the adjacent tubes but largely reflected back into the burning gases materially aiding in completing combustion before the entrance to the first pass is reached.
- 10 10 A wide throat is provided by the inclined baffle 11 insuring low entering velocity and freedom from slag trouble. The cross baffles direct the gases across the tubes three times, all dead spaces are eliminated and a
- 15 15 maximum rate of heat transfer is maintained. A substantially uniform gas velocity can be maintained by properly proportioning the area of the gas passages to compensate for the shrinkage of the gases as they cool. This
- 20 20 will tend to keep soot and ash in suspension until the expansion of the gases in the enlarged space above the top baffle 13, will slow the velocity, and suspended matter will deposit on top of baffle 13, whence it can be
- 25 25 readily removed.

30 By the arrangement shown, the maximum efficiency as shown by low flue gas temperatures, and the maximum capacity with the lowest draft loss from the furnace 3 to the boiler outlet 14, is obtained.

35 What I claim is:

35 In a boiler of the water tube type having a furnace at the front end and comprising a bank of tubes inclined from front to rear, upright headers at the ends of the tubes and a steam and water drum above the headers with which they communicate, a combustion chamber below the forward end of the boiler with a bridge wall at its rear end, a baffle around

40 40 the lower row of tubes extending rearward from the front header a part of the length of the tubes and terminating directly above the bridge wall, a cross baffle extending upward and to the rear from the end of the

45 45 baffle at an obtuse angle to such baffle, a third baffle on one of the upper rows of tubes extending from the rear header forwardly a part of the length of the tubes, and a cross baffle extending downward from the end of

50 50 said last baffle at an obtuse angle to such baffle.

55 In testimony whereof, I have hereunto subscribed my name this 25th day of November, 1929.

55 KINGSLEY L. MARTIN.
